HEAT EXCHANGER FOR OIL COOLERS

Howard F. Brinen, Racine, Wis., assignor to
 Young Radiator Company, Racine, Wis., a company of Wisconsin

Application May 9, 1941, Serial No. 392,705

3 Claims. (Cl. 257—2)

The present invention relates to means for controlling the temperature of internal combustion engine lubricating oil and is particularly adapted for use with aviation engines and is offered as an improvement over the design shown in a pending application John J. Hilt inventor, Serial No. 364,236, filed November 4, 1940.

An object of the present invention is to provide a conventional design having two headers and a number of preferably similar tubes forming operating connections therebetween and a multiplicity of closely spaced strip fins through which the tubes extend forming a unitary core.

Another object of the present invention is to provide a conventional design having means whereby the lubricating oil is first passed through low resistance low heat transfer capacity tubes while at low temperature and then through a large number of high resistance tubes after the oil reaches a predetermined temperature.

The above objects are accomplished by providing a unitary core having a few front tubes of low heat transfer capacity and offering low resistance to the flow of oil therethrough and a large number of high resistance tubes in the rear and a partition between the front and rear tubes in one of the headers having a valve adapted to permit the oil when too viscous to pass through the high resistance tubes to pass through the low resistance tubes.

In my new design, I use tubes in the rear bank of tubes which are preferably similar to the front tubes but are provided with turbulence strips. In order to provide a high resistance path, I may provide a large number of very small tubes so hot oil will flow therethrough freely but the oil will not flow therethrough when chilled. Therefore it may be said that the lubricating oil will be permitted to heat quickly after which it will pass through the rear bank of tubes and be effectively cooled.

Another object of the present invention is to position the low resistance tubes in a transverse row at the air entrance or front side of the device and arrange the by-pass valve so when the oil will not pass through the high resistance tubes, it will raise the valve and be permitted to pass through these low resistance tubes.

A further object of the present invention is to provide means whereby the oil will be permitted to heat quickly because of the limited number of tubes through which it first passes and the limited cooling area exposed to the air but to permit the heated air to then come in heat exchange

contact with the high resistance tubes and their portions of the fins.

A still further object of the present invention is to provide a device for the purpose which will be unitary, compact, light, neat in appearance and durable which can be manufactured at low cost.

Another object of the present invention is to provide an aperture in the valve partition whereby a predetermined volume of oil will be permitted to pass from the high resistance end of the header to the low resistance end of the header when the valve is closed; thus to utilize the low resistance tubes and their portion of the fins to cooperate with the high resistance tubes in normally cooling the oil.

To these and other useful ends, my invention consists of parts, combinations of parts, or their equivalents and mode of operation, as hereinabove set forth and claimed and shown in the accompanying drawing in which:

Fig. 1 is a front view of my improved oil cooling device.

Fig. 2 is a transverse sectional view of the device shown in Figure 1, taken on line 2—2 of this figure.

Fig. 3 is an end view of one of the high resistance tubes and the agitating means therein.

Fig. 4 is a longitudinal section through a fraction of one of the high resistance tubes, illustrating the agitating means therein.

Fig. 5 is a view of the agitating means before the body is zig-zagged as shown in Figure 4.

Fig. 6 is a sectional view of a modification taken on line 6—6 of Figure 7.

Fig. 7 is a longitudinal sectional view of the modification shown in Figure 6.

As thus illustrated, my improved device comprises a lower header 10 and an upper header 11, the lower header being conventional and the upper header being equipped with a partition 12 arranged between the low resistance row of tubes and the high resistance bank of tubes.

Partition 12 is shaped as shown and provided with preferably a forwardly curved projection 12^a having an aperture 12^b and an opening 13 formed with a seat as at 15 for a valve 14, the valve having a stem 16 which is slidably mounted in a cap 17, as illustrated, the cap being screw threaded into an extension chamber 18 which is concentric with opening 13 and registering with member 12^a.

I provide a spring 19 for holding the valve on its seat against a predetermined pressure. The headers are operatively connected together

by means of preferably a front row of circular in cross section tubes 20 and a number of rows of circular in cross section tubes 21.

Tubes 20 and 21 are provided with a multiplicity of closely spaced fins 22 through which the tubes extend and to which they are bonded in the usual manner. In designs of the class, it is customary to either form the header with separate tube plates which are removably secured to the header caps or the outer surface of the headers are provided with threaded apertures which register with the tubes for the reception of the expanding tool with which to expand the tube ends into the headers after which the apertures are closed preferably by means of pipe plugs. These methods are too well known to require further description or to require illustration in the present drawing.

Tubes 21 are provided with agitating strips which in their entireties are designated by reference character A. I have shown the preferred form of strip although many other well known designs may be used. Strips A are first formed from flat stock, as illustrated in Figure 5 and then they are bent into the shape shown in Figure 4, the strips comprising connecting members 23 and spaced cross members 24 each having an opening 25, the ends of which are cut free forming strips 26, the strips being bent outwardly as illustrated in Figure 4 so as to practically prevent a straight through path in the tubes.

When the strips are designed and bent as illustrated in Figure 4, very small straight through openings 27 and 28 are provided but these openings are not very effective for the passage of oil because the oil is diverted violently back and forth by members 23, 24 and 26, the oil being caused to violently impinge the walls of the tubes thus to increase the heat transfer capacity of the tubes and provide means whereby when the oil is quite thick or viscous, it will not readily pass through the tubes.

Clearly the resistance offered to the passage of chilled oil through tubes 21 may be sufficient to cause a pressure which will lift valve 14 so the oil will practically all pass through tubes 20 and since these tubes have a limited heat exchange area in contact with the blast of moving air through the core, as indicated by single pointed arrows, the oil will be permitted to heat quickly after which heat transfer will take place from the heated oil and heated air into the oil in tubes 21. Thus the chilled stagnant oil in tubes 21 will be heated so in time valve 14 will be permitted to close and all of the oil forced through tubes 21 after which it will be adequately cooled by the air blast and its contact with the fins and tubes.

In the present design, the headers form the upper and lower retainers of an air duct. I provide plates 30-30 which are secured to the ends of the headers having narrow flanges 31 which embrace the front and rear sides of the headers and protect the corners of the fins. These plates form the side members of the air duct.

In Figure 2 I have illustrated the direction of oil flow when the valve is closed by double pointed arrows.

It is generally the custom to force the blast of

air between the fins and tubes by means of frontal pressure. It will be understood that my device may be used for cooling the oil on stationary engines by simply providing the device with an air moving fan similar to automobile radiators.

In Figures 6 and 7 I illustrate tubes 35 which are flattened and having therein an agitating strip comprising transverse members 36 having openings 37 therein and being connected together by means of connecting members 38, the strips being zig-zagged somewhat similar to that shown in Figure 4. This design of tube may be used in place of tubes 21 in Figure 2 and they may also be supplied as a substitute for tubes 20 wherein no agitating strips would be needed.

Aperture 12^b permits some oil to pass through tubes 20 when valve 14 is closed. Thus when the valve is closed and the oil is hot, some of it will pass through tubes 20 and be cooled thereby.

Clearly many minor detail changes may be made in the present invention without departing from the spirit and scope of this invention as recited in the appended claims.

Having thus shown and described my invention, I claim:

1. A unitary oil temperature controlling device comprising spaced headers having inlet and outlet connections in their rear sides and being operatively connected together by a number of rows of tubes, a multiplicity of closely spaced strip fins through which said tubes extend, whereby a blast of air may be forced between said tubes and fins from the front thereof, at least one front row of tubes being adapted to offer little resistance to the flow of oil when chilled, the other tubes being adapted to offer great resistance to the flow of oil when chilled, a partition in one of said headers separating the low from the high resistance tubes and having a relief valve adapted to permit the oil to pass through the low resistance tubes when it cannot pass through the high resistance tubes, said rear bank of tubes having therein agitators adapted to prevent a free flow of oil therethrough.

2. A unitary oil temperature controlling device comprising two spaced headers having inlet and outlet connections in their rear sides and being operatively connected together by a number of rows of tubes, a multiplicity of closely spaced strip fins through which all of said tubes extend and in metallic contact therewith, whereby a blast of air may be forced between said tubes and fins from the front of the device toward the rear thereof, at least one row of tubes positioned at the front of the device being adapted to offer little resistance to the flow of oil when chilled, the other tubes being adapted to offer great resistance to the flow of oil when chilled, a partition in one of said headers separating the low from the high resistance tubes, a by-pass valve adapted to permit the oil to pass from the high resistance to the low resistance side of said partition when it cannot pass freely through the high resistance tubes.

3. A device as recited in claim 2 including: a relatively small permanently opened aperture adapted to permit free passage of oil directly from the high pressure to the low pressure side of the partition.

HOWARD F. BRINEN.
